UNITED STATES PATENT OFFICE.

CHARLES S. EVENS, OF WALDEN, NEW YORK, ASSIGNOR TO NEW YORK KNIFE COMPANY,
OF NEW YORK, N. Y., A CORPORATION OF NEW YORK.

POCKET-KNIFE.

1,264,625.

Specification of Letters Patent.

Patented Apr. 30, 1918.

Application filed August 21, 1916. Serial No. 115,988.

To all whom it may concern:

Be it known that I, CHARLES S. EVENS, a citizen of the United States, residing at Walden, in the county of Orange and State 5 of New York, have invented certain new and useful Improvements in Pocket-Knives, of which the following is a specification, reference being had therein to the accompanying drawing.

10 This invention relates to pocket knives in which a blade is swingably mounted to a handle so that it can be opened and shut.

Sometimes pocket knife blades are used in such manner as to involve the danger of 15 accidental shutting up of the knife; such for example as the pocket knife punch blade disclosed in Patent No. 1,171,422, dated February 15, 1916.

The principal object of the present improvement is to provide a simple and practicable device which is operable when the 20 blade is open, to lock the blade against swinging shut, thus eliminating the danger referred to.

25 Other objects hereof will appear in the hereinafter following description of one form in which the knife may be embodied.

To the attainment of the objects and advantages referred to, the present invention 30 consists in the novel construction, combination and other features illustrated, described, or claimed herein.

In the accompanying drawings forming a part hereof, Figure 1 is a side view of a 35 pocket knife, provided with a punch blade and embodying the present improvement, the same shown with the blade locked open.

Fig. 2 is a similar view with the open blade unlocked.

40 Fig. 3 is a similar view with the blade swung partly shut.

Fig. 4 is a central longitudinal section of part of Fig. 1.

Fig. 5 is a similar section of a part of 45 Fig. 2.

Fig. 6 shows, in perspective, the blade and lock device removed.

Fig. 7 shows, entirely detached from each other, all of the parts directly involved in 50 the present invention.

The ordinary pocket knife handle 7 is shown, the same having the usual interior recess or grooves 8 into which knife blades may be folded. An ordinary cutting blade 55 9 is shown pivoted at the lower end of the

knife, although the presence of this blade does not affect the present invention.

The punching blade 11 is pivoted at the upper end of the handle. This blade comprises the tang 12, perforated at 13 for 60 the reception of the usual pivot pin, and the usual back-spring 14 is indicated, by which the blade is yieldingly held in closed, half-open, or open position.

The punch blade 11 is provided with a 65 sharp stabbing point 15, and it will be understood that in the use of this blade the handle is given a rotating motion, while the point 15 is thrust into the leather, rubber, or other material to be punched. 70 It is in the process of performing this punching or reaming operation that the danger is incurred of accidental shutting of the knife.

According to the present invention, a 75 movable lock device is employed, operable when the blade is open to lock the blade against swinging shut. This lock device comprises essentially a swinging latch or lug 25, which will preferably be mounted on the blade member, while the other or 80 handle member is formed with a recess or shoulder 26. These parts are so arranged that when the knife blade is open and the latch is swung outwardly, it engages in the recess and thereby prevents accidental 85 closing.

Preferably I move the latch from its non-locking position shown in Fig. 2, to its locking position shown in Fig. 1, by hand, for example with the finger nail, although this 90 movement could be made automatic, if desired. Being able to retain either position in which it is set by hand, the blade is easily shut when desired without the need of maintaining the pressure of the finger on 95 the latch.

The space provided in the pocket knife handle for the accommodation of the parts of this invention is extremely limited, but the following structure of the parts gives 100 an inexpensive and practicable arrangement which does not interfere with the strength and durability of the knife.

The tang 12, rather than being solid as usual, is built up. The particular arrangement shown may be described as a split tang, it being formed in two mutually contacting flat plates, 27 integral with the blade, and 28 non-integral. The hole 13 for the blade pivot pin is shown as extending 110

through both tang portions and also through the handle portion (see Fig. 7). In order to hold the parts in proper registry, an additional pin 29 is provided on the tang part 28, engaging a corresponding hole 30 in the tang part 27.

The latch 25 has its fulcrum located between the two tang parts, and for this purpose there is provided a transverse groove 31 in one of the tang parts, engaged by the laterally extending fulcrum pins 32 of the latch. Also, the tang part 28 is recessed at 33 to correspond with the recess 26 in the handle, so as to accommodate the latch 15 in its swinging movements.

It will thus be seen that I have described a pocket knife embodying the features of invention referred to and attaining the objects and advantages cited, and other advantages will be apparent to those skilled in the art. It is manifest that matters of size and proportion, contour and details may be variously modified without sacrificing the advantages of the invention, and therefore no limitation to such details is intended, except in so far as is specified in the appended claims.

Copies of this patent may be obtained for five cents each, by addressing the "Commissioner of Patents, Washington, D. C."

What is claimed is:

1. A pocket knife comprising a handle having a locking recess, and a blade pivoted thereto to swing open and shut, said blade having a built-up tang, and a latch movably mounted between the tang parts adapted to be positioned in said recess to lock the blade open. 30

2. In a pocket knife the combination of a grooved handle having a locking shoulder at one extremity, and a blade pivoted to such end of the handle to swing edgewise from and into the groove of the handle, together with a movable non-resilient lock device swingably mounted on the blade and adapted to retain an inoperative position flat against the blade, but to be shifted at will when the blade is open to engage with 40 said shoulder of the handle and lock the blade rigidly in open position. 45

In testimony whereof, I have affixed my signature in presence of two witnesses.

CHARLES S. EVENS.
